Joseph A. Miller ATTORNEY.

UNITED STATES PATENT OFFICE.

LOUIS E. SADLER, OF ATTLEBORO, MASSACHUSETTS, ASSIGNEE TO THE F. H. SADLER COMPANY, OF ATTLEBORO, MASSACHUSETTS.

SAFETY DEVICE FOR PINS.

Application filed May 5, 1922. Serial No. 553,559.

To all whom it may concern:

Be it known that I, LOUIS E. SADLER, a citizen of the United States, residing at Attleboro, in the county of Bristol and State 5 of Massachusetts, have invented new and useful Improvements in Safety Devices for Pins, of which the following is a specification.

This invention relates to certain new and 10 useful improvements in safety devices for pins and the like, and the primary object thereof is to provide a device of this kind which is of simple and economical construction and which is efficient in operation so as 15 to completely house and protect the pointed end of the pin and to prevent accidental movement thereof out of the keeper.

A further important object of the invention is to provide a device of this character 20 which may be formed in part integral with the pin structure, or which may be made separate therefrom and then suitably secured to the pin structure.

The invention still further aims to provide 25 a device of this character which involves a minimum of parts and material, and in which, in the instance of being formed integral in part with the pin structure, eliminates the use of solder and all other separate fastening means.

The invention also aims to provide a device of this type which can be easily operated and which still is effective as a safety device, and has still further and other objects 35 which will be later set forth and manifested in the course of the following description.

In the drawings:—

Figure 1 is a bottom plan view of the invention;

Figure 2 is a side elevation;

Figure 3 is a section on line 3—3 of Figure 2;

Figure 4 is a section on line 4—4 of Figure 1, and

Figure 5 is a perspective view of the base of the device in the instance of the formation of the device entirely separate from the pin.

In proceeding in accordance with the present invention the pin body 1 is shown as being of approximately U-cross section, having the pin 2 pivoted thereto at one end as

usual. The sides of the body 1 are formed with an integral part 3, which latter is 55 formed into a tubular formation 4 connected by contracted neck portions 5 to the sides of the body 1, the tubular portion 4 serving to house or receive therein the pointed end of the pin 2. The tubular portion 4 is slotted 60 as indicated at 6, the slot extending lengthwise thereof and terminating short of the rear end of the same so as to provide a stop or abutment 7. A sliding member 8 is mounted on the tubular portion 4 and has 65 its side edges inturned as indicated at 9 so as to prevent rotation of the member 8 about the portion 4, the inturned sides 9 engaging in the concavities formed by the neck portions 5. The forward end of the slidable 70 protector 8 is formed with a struck-out lug 10 which engages through the slot 6 of member 4 and with the stop 7 so as to limit sliding movement of the protector 8 to open position. The rear end of the member 8 may 75 be closed as shown at 11 so as to engage the opposite or rear end of the part 4 to thereby restrict movement of the protector 8 to operative position and to present a neat appearance. The sides of the member 8 may 80 be knurled or roughened as indicated at 12 so as to enable the fingers of the user to grasp same firmly. In addition, the forward ends of the base member 4 are slightly spread, so that the latter has a somewhat 85 wedge shape, and the protector 8 is given a corresponding shape, so that the end wall 11 may be dispensed with, and movement of the protector to operative position limited by the wedge shape of the parts as just described. 90

By referring to Figure 5 it will be seen that the base member therein shown is formed separately from the pin body 1 and may be secured thereto in any desired manner, such 95 as by soldering, the base member including a tubular portion 4' and contracted neck portions 5' and a slot 6', the structure being identical in all essentials to that above described.

From the foregoing it will be seen that in order to secure the pin and to release same, it is merely necessary to slide the protector 8 according as to whether the pin is to be removed or housed, and that the wedge shape 105 of the parts affords a frictional latching

means which prevents accidental movement and thereby opening of the protector to release the pin.

Having thus described my invention, what I claim as new and desire to secure by Letters Patent is:—

1. A pin protector including a base part having a tubular portion and a contracted neck, the base part being carried by the body 10 of the pin and being of wedge shape and having a longitudinal slot extending through one end of the tubular portion thereof, and terminating short of the other end, a protector of tubular form and wedge shape slid- 15 able on the base part and having its sides engaging in the neck of the base part, and a lug struck out from the forward end of the protector and engageable in the slot of the base part and with the inner end wall 20 formed by the slot.
2. A pin protector including a base member having a tubular pin-receiving part formed with a slot which latter affords a stop at one end, and a protector member of 25 tubular form slideable over the base member and having a lug which projects inwardly therefrom into the slot and having a closed rear end which engages the rear end of the base member.
3. In a pin protector, a wedge-shaped base member having a tubular part slotted to receive the pin therein, and a member slide- 30 able on the base member and having wedge-like engagement therewith to cover the slot and hold the pin in the base member.
4. In a pin protector, a hollow base mem- 35 ber of wedge shape slotted to receive the pin end, and a wedge shaped member slideable on the base member to cover the slot.
5. In a pin protector, a hollow base mem- 40

ber having a slot and contracted parts, and a protector member slideable over the base member to cover and uncover the slot and having its sides engaged in the contracted parts of the base member.

6. A pin protector including a hollow base member slotted to admit the pin to the interior thereof, a slideable tube-like member disposed over the exterior of the base member to cover the slot, and having a closed rear end to engage the rear end of the base member to limit sliding of the slideable member in one direction, means to slidably mount the second member on the base member and to hold same against rotary movements, and means to limit sliding of the slideable member in the opposite direction.

7. A pin protector including a hollow slot- 55 ted base member having a neck portion se- cured to the body of the pin, a split mem- ber mounted over the base member and re- ceiving the neck portion in the split there- of, and means to limit sliding of the split member.

8. In a pin protector, a hollow base mem- 60 ber having a contracted neck and having a slot to receive the pin, and a protector mem- ber slideably mounted over the base member and having a part extending through the slot and into the interior of the base mem- ber to dispose the pin end in the contracted neck of the base member.

In testimony whereof I have signed my name to this specification in the presence of two subscribing witnesses.

LOUIS E. SADLER.
